(57) CLAIM

The ornamental design for a toy figure, as shown and described.

DESCRIPTION

FIG. 1 is a front-elevational of a toy figure according to one embodiment of the claimed design;

FIG. 2 is a rear-elevational view thereof;

FIG. 3 is a first side elevational view thereof;

FIG. 4 is a second side elevational view thereof;

FIG. 5 is a top plan view thereof;

FIG. 6 is a bottom plan view thereof; and,

FIG. 7 is a perspective view thereof.

Broken lines (if any) showing the environment in any figures are for illustrative purposes only and form no part of the claimed design.
